(57) **CLAIM**

The ornamental design for a set of decorative braids for a bicycle helmet, as shown and described.

DESCRIPTION

FIG. 1 is a left side view of a set of decorative braids for a bicycle helmet showing my new design;

FIG. 2 is a right side view thereof;

FIG. 3 is a front elevation thereof;

FIG. 4 is a rear view thereof.

FIG. 5 is a top plan view thereof; and,

FIG. 6 is a bottom plan view thereof.

The bicycle helmet shown in broken lines is for environmental purposes only and forms no part of the claimed design.

1 Claim, 4 Drawing Sheets

FIG. 5

FIG. 6
